UNITED STATES PATENT OFFICE.

MAX ROCKSTROH, OF KLEIN-SEDLITZ, NEAR PIRNA, GERMANY.

PROTECTIVE DEVICE FOR PRINTING AND EMBOSsing PRESSES.

1,169,680.

Specification of Letters Patent. Patented Jan. 25, 1916.

Application filed April 10, 1914. Serial No. 830,959.

To all whom it may concern:

Be it known that I, MAX ROCKSTROH, manufacturer, a subject of the King of Saxony, Germany, residing at Klein-Sedlitz, near Pirna, Saxony, Germany, have invented certain new and useful Improvements in Protective Devices for Printing and Embossing Presses, of which the following is a specification.

10 My invention relates to protective devices for printing and embossing presses.

Protective devices are already well-known in which a grating which covers the dangerous gap between the platen and table is employed for throwing the machine out of gear, but these guards afford no protection against putting the hands into the rolls.

15 The present invention which affords the most perfect protection that can be expected of such a device provides a sheet-metal plate or grating which covers over the inking rollers and swings up and down in a position approximately parallel to itself; this arrangement is connected with a number of 20 new effects which are enumerated hereinafter: 1. The hands are protected from the dangerous rotation of the rollers. 2. The protective grating is located in its elevated position when the platen is in its open position and leaves the table perfectly free for 25 the purpose of lifting the form and the platen for the purpose of making the form ready or inserting the sheet of paper. 3. The protective grating in its elevated position is arrested in front of the rollers against movement toward the rear, whereas 30 in its lower position it is able to yield toward the rear and also upward in order entirely to prevent the fingers being jammed between 35 the top edge of the platen and the guard without impairing the reliability of the function of the latter. 4. After the guard 40 has been lowered and the machine has begun to be thrown out of gear in the case of danger, the guard rises at once; the hand still resting on the platen is released from the guard and is not held clamped between the platen and the guard. 5. The hand resting 45 on the platen can never be clamped between the protective bar and the upper edge of the platen as was readily possible heretofore.

50 Figure 1 is a side view of the device attached to a press. Fig. 2 is a top plan view of the same. Fig. 3 is a similar view as Fig. 55 1, with the grate in elevated position. Fig. 4 is a side view of a modified form of the

device. Fig. 5 is an end view thereof. Fig. 6 is a view similar to Fig. 4 with the grate at the beginning of its upward movement. Figs. 7, 8 and 9 are detailed views. 60

The guard, which may be of any desired material and of any suitable shape consists, for example, in the present case of a grating *a* attached to a frame *b* which is pivotally suspended from the ends of the levers *c* fast 65 on the common spindle *d*. The guard is steered by means of a cam *f*, mounted for example on the main gear-wheel *e*, through the medium of the anti-friction roller *g* of the lever *h* and the connecting-rod *i*. The 70 parallel motion of the guard is effected by means of a guide lever *k* comprising two telescopic parts *k* and *l* connected by a spring *m* which allows the guard to yield in the direction of the table. 75

The operation is such that when the machine is running normally the projection *o* of the frame *b* bears on a pin *r* of the safety levers *s*, so that the lug *p* of this lever moves over the arm *q* of the engaging lever *t*; if 80 the hand of the operator is still resting on the platen, however, the safety lever *s* remains in its disengaging position. The lug *p* bears against the arm *q* and the machine 85 is thrown out of gear and the brake is applied.

Another form of the invention as applied to a high-speed press is shown in Figs. 4 to 9. In these figures *a* designates the reciprocating table, and *b* the protective grating which swings up and down and is suspended from the two levers *c*. These levers are fast on a spindle *d* journaled in the sides of the frame *e*. The guard *b* is steered by the cam-shaft *f* through the medium of the 90 anti-friction roller *g*, the lever *h* and the rod *i*. Attached to the table is a rail *k* adapted to coact with a friction clutch *l* which is connected by the connecting rod *m* and the rod *n* with the disengaging rod *o*. 100 The clutch *l* is so arranged that it can be driven by the rail *k* in only one direction; this is effected by the knee-lever action with which the upper friction jaw *p* bears against the rail *k*. The jaw *p* is moved into its 105 releasing position by the projection *q* of the guard *b* which bears on the angle lever *s* on which the jaw *p* is suspended. The action is analogous to that of the device described above inasmuch as when the machine 110 is working normally the projection *q* of the guard *b* bears on the angle lever *s*, whereby

the friction jaw *p* remains elevated, so that the rail *k* can slide unimpededly through the clutch. When the guard is in its raised position the table is moving backward; in spite of the friction jaw not being lifted from the rail *k* the latter will slide through nevertheless in consequence of the friction acting in only one direction. If the guard is moved toward the rear in case of danger, for example when a hand or some object is left lying on the table then the friction jaw loses its support, it moves into its frictional position and the machine is thrown out of gear. In order to accelerate the disengagement of the machine the disengaging rod is connected not only with the flywheel brake, but also by known means, which need not be described in detail, with the brake of the carriage and cylinder.

Copies of this patent may be obtained for five cents each, by addressing the "Commissioner of Patents, Washington, D. C."

I claim:—

A protective device for printing and embossing presses comprising in combination, a substantially vertical guard grate, in front of the inking rollers of the press, means for raising said grate and holding it in its elevated position against rearward movement, and means for lowering the grate and allowing a rearward and upward movement of the same for the protection of the hands of the operator.

In testimony whereof I have hereunto set my hand in presence of two subscribing witnesses:

MAX ROCKSTROH.
